UNITED STATES PATENT OFFICE.

SAMUEL R. HUNTER, OF MISHAWAKA, AND JOHN W. ARNOLD, OF SOUTH BEND,
INDIANA.

BOX FOR MAIL AND THE LIKE.

Application filed July 16, 1924. Serial No. 726,295.

The present invention, although applicable to other uses, is particularly intended for use in apartment buildings or other places where mail is deposited by mail carriers in boxes 5 that are accessible to the public or at least to others than the person or persons for whom the mail is intended; and its object, specifically considered, is to produce a simple and novel construction and arrangement which 10 shall contain a plurality of compartments of considerable depth, without concealing an objectionably large portion of the surface of a wall to which it may be applied, and which will make it possible for the mail carrier to 15 open all of the compartments by the operation of a single door without permitting the owner or user of one compartment to gain access to any other compartment.

Viewed in one of its aspects the present invention may be said to have for its object to 20 produce a simple and novel multiple-compartment box provided with a single door or closure common to all of the compartments and with individual doors for the several 25 compartments.

A further object of the present invention may be said to be the production of a simple and novel multiple-compartment box so constructed and arranged that a single, comparatively small door gives entrance simultaneously to all of the compartments when the door is opened, thereby making the height of the door independent of the height of the box and permitting the latter to be made of any 35 height desired.

The various features of novelty whereby our invention is characterized will hereinafter be pointed out with particularity in the claims; but, for a full understanding of our 40 invention and of its objects and advantages, reference may be had to the following detailed description taken in connection with the accompanying drawing, wherein:

Figure 1 is a front elevation of a device arranged in accordance with the present invention, set into a wall, a fragment of the wall being shown; Fig. 2 is a section taken approximately on line 2—2 of Fig. 1; Fig. 3 is a vertical section, on a larger scale, through 50 the hinged joint between the main door and the box, showing a slightly modified construction; and Fig. 4 is a front view of a fragment of the box, showing one of the hinges illustrated in Fig. 3.

Referring to the drawing, 1 represents a

casing made out of any suitable materials and of any desired height and width. The particular construction shown is designed for use in apartment buildings and the casing is therefore made of such a depth that it may 60 be set into a wall of a hall or lobby that is accessible to the public. The casing is divided into any desired number of vertical compartments, arranged side by side, by means of partitions 2. For the sake of illustration 65 only four such compartments are shown, but it will be understood that this number may be varied by simply varying the width of the casing and adding more partitions. It is desirable that the individual compartments, 70 each of which constitutes a mail-receiving receptacle, be made rather high so as to be capable of receiving long pieces of mail. However, it is not desirable that too large a 75 superficial area be exposed when the device is set in a wall; not only for the sake of appearance, but also to avoid the necessity of manufacturing an unduly large, expensive front plate or wall. We have therefore designed the device so that the door openings have 80 only a fraction of the height of the mail compartments, the door openings being preferably in the lower portions of said compartments so that the mail will be exposed to view 85 when the doors are opened.

For convenience in placing mail in the several compartments of the box, there should be a single door common to all of the compartments and, in order that each tenant or user may have access to his own mail but not 90 to that in other compartments, each compartment should have an individual door. We have therefore provided the box with a door 95 3 extending across all of the compartments, so as to be common thereto, and in this main door we have arranged individual doors 4, one for each compartment. Since the main door has a vertical dimension much less than the height of the box, it may conveniently be mounted in a front plate 5 taking the form 100 of a rectangular frame surrounding the door and also having a vertical dimension much less than the height of the box. This front plate or frame extends across and forms the front wall for the lower portion of the box, while the front wall 6 for the upper portion of the box is set back some distance from the plane of the wall 5. This arrangement permits the box to be set into a wall 7 of the thickness that is usually employed in halls or 105 110

lobbies of apartment buildings, with a layer of plastering 7^a extending down over the wall 6, but with its outer surface substantially flush with the wall 5 that contains the doors. When the box or receptacle is mounted in the wall, the only portions thereof that are exposed are the frame 5 and the doors; and therefore only this frame and the doors need be made heavy and of such materials and design as not to detract from the appearance of the place in which the mail box is used, the body of the casing and the partitions being made of any suitable serviceable materials.

15 The main door is supported in its frame by suitable hinges which are preferably arranged between the top of the door and the upper member of the door frame, as indicated at 8 and 9. The auxiliary or individual doors 20 are preferably hung on hinges 10 whose axes are vertical. The main door may be held closed by suitable lock 11 adapted to be opened only by a key carried by the postman. Each auxiliary door is provided with its own 25 lock as indicated at 12. When mail is to be deposited in the box, the postman simply unlocks the main door, which then is swung up into the position shown in dotted lines in Fig. 2, either automatically or otherwise, giving 30 him access to all of the compartments. When a tenant desires to withdraw mail, he simply unlocks the door to his particular compartment, but does not thereby gain access to any other compartment.

35 Suitable spring means may be provided for swinging the main door into its open position. A simple way of applying such a spring is to employ a spring hinge such as illustrated at 13, Figs. 3 and 4; 14 indicating the spring 40 which is placed under tension when the door is closed and therefore, as soon as the door is unlocked, acts to swing it open. Where such spring-opening means are employed, the postman must push the door shut against the resistance of the spring or springs, after having 45 placed the mail in the box. If it is not desired to cause the door to swing open automatically when it is unlocked there may be employed a suitable catch or strut for holding the door open after it has been manually opened; so that the postman need only trip the catch or support and permit the door to drop into its closed position by gravity. Such an arrangement is shown in Fig. 2. Referring to this 50 figure, it will be seen that on the inner side of the main door is a curved bar 15 hinged at one end, as indicated at 16, to the main door at some distance below the upper edge of the latter. Near the free end of the bar is a 55 notch 17 that is adapted to engage with a pin 18 projecting laterally from one of the side walls or one of the partitions of the box when the door is swung open, and serve as a supporting strut for holding the door open. 60 When the door is to be closed, the postman

simply pushes the lower end of the bar or strut upwardly far enough to bring the notch 17 clear of the pin 18, whereupon the door will drop down by gravity and the bar will move from the dotted line position in Fig. 2 65 into the full line position.

It will thus be seen that we have devised a simple multiple compartment receptacle, particularly applicable for use as a multiple mail box, which is adapted to receive long pieces of 70 mail; without exposing on the face of a wall in which the box is set an objectionably large metallic area; and which will permit the postman easily and conveniently to place mail in 75 all of the compartments and the tenants or users each to withdraw his own mail, and will not permit the placing of circulars or other objects and things into the box by unauthorized persons.

While we have illustrated and described 80 with particularity only a single preferred form of our invention, with a slight modification, we do not desire to be limited to the specific details thus illustrated and described; but intend to cover all forms and arrangement that come within the definition of our invention constituting the appended claims.

We claim:

1. A device of the character described, comprising a casing divided into a series of vertical compartments arranged side by side, the upper portion of the casing being shallower from front to rear than the lower portion to permit the upper portion to lie behind a wall with which the lower portion is flush, a main door on the front of said lower portion common to all of the compartments, said main door being hinged to swing about a horizontal axis at its upper edge, means tending constantly to open said main door, individual doors for said compartments in the aforesaid door, and a separate lock for each door. 100

2. A device of the character described, comprising a casing divided into a series of vertical compartments arranged side by side, the lower portion of the casing projecting outwardly beyond the upper portion so as to permit it to lie flush with a wall concealing the shallower upper portion, a door common to all of said compartments extending across the front of said lower portion of the casing and mounted so as to be capable of swinging outwardly about a horizontal axis, individual doors for said compartments in the aforesaid door, and a separate lock for each door. 110

3. A device of the character described, comprising a casing divided into a series of vertical compartments arranged side by side, the lower portion of the casing projecting outwardly beyond the front of the upper portion, a plate at the front of the lower portion projecting upwardly beyond the lower end of the upper portion so as to permit it to lie flush with a wall concealing the shallower upper portion, a door common to all of said com- 125

partments extending across the front of said lower portion of the casing and mounted so as to be capable of swinging outwardly about a horizontal axis, adjacent to its upper edge, 5 individual doors for said compartments in the aforesaid door, and a separate lock for each door.

4. A device of the character described, comprising a casing divided into a series of vertical compartments arranged side by side, the lower portion of the casing projecting outwardly beyond the upper portion so as to permit it to lie flush with a wall concealing the shallower upper portion, a door common 15 to all of said compartments extending across the front of said lower portion of the casing and mounted so as to be capable of swinging outwardly about a horizontal axis, adjacent to its upper edge, individual doors for said 20 compartments in the aforesaid door, and a

separate lock for each door, and means for holding the first-mentioned door open.

5. A mail receptacle consisting of a casing situated in a wall opening and having a back wall, top, bottom and side walls extending outwardly perpendicularly to said back wall, certain of said perpendicularly extending walls being shorter than the other perpendicular walls so that a portion of the casing will be flush with the outer edge of the wall supporting the same and the remaining portion will be concealed beneath said wall, said casing being divided into compartments, a master door for all the compartments and individual doors in said master door giving access to each compartment. 25 30 35

In testimony whereof, we sign this specification.

JOHN W. ARNOLD.
SAMUEL R. HUNTER.
